UNITED STATES PATENT OFFICE.

CHARLES J. CALLAHAN, OF ATTLEBORO, MASSACHUSETTS.

CUFF-BUTTON.

1,187,967.

Specification of Letters Patent. Patented June 20, 1916.

Application filed April 13, 1916. Serial No. 90,973.

To all whom it may concern:

Be it known that I, CHARLES J. CALLAHAN, a citizen of the United States, and resident of the city of Attleboro, in the county of Bristol and State of Massachusetts, have invented certain new and useful Improvements in Cuff-Buttons, of which the following is a specification.

This invention relates to cuff buttons of the class constructed of two members detachably connected together, and the object of this invention is to provide a cuff button having two members adapted to be readily connected to and disconnected from each other and of a class more particularly designed for retaining soft cuffs, each member of the button having two spaced apart heads of a size to be retained in the cuff fabric even when the members are disconnected from each other.

A further object of the invention is the provision of a pair of elongated spring arms mounted in the tubular post on one of said members, said arms being fulcrumed against each other at a point intermediate their opposite ends for the purpose of stiffening the inherent spring in the arms.

A further object of the invention is to so shape this spring arm member that it will fit the tubular post of the button member, thereby positively controlling the opening action of the head portion of these arms, causing them to remain under a given tension even when in their spread position.

With these and other objects in view, the invention consists of certain novel features of construction, as will be more fully described, and particularly pointed out in the appended claims.

In the accompanying drawings: Figure 1— is a side elevation of my improved separable button. Fig. 2— is a central sectional view through the button. Fig. 3— is a central sectional view through one of the button members, showing the spring arms in full and mounted therein. Fig. 4— is a top view of the spring arms spread apart as cut from sheet stock and swaged into a concave form. Fig. 5— is an edge view of the spring arms in extended position. Fig. 6— is a detail showing a sectional side elevation of the spring arms bent up into operative position with their edge walls abutting at a point intermediate their opposite ends. Fig. 7— is a back view of the spring arms in elevation. Fig. 8— is a sectional end

view on line 8—8 of Fig. 6 looking in the direction of the arrow showing the concavo convex shape of the arms.

Like reference characters indicate like parts throughout the several views.

Referring to the drawings the shells of the two opposite button members 10 and 11 are herein shown as being similarly constructed. The member 10 being provided with a post 12, one end of which is spread forming a head 13 with a rounding outer surface 14, the opening 15 through this head into the post member is slightly contracted at its edge forming an annular shoulder 16 for engaging the head of the spring arms presently described. A plate 17 is rolled onto the outer end of this tube 12 which outer end is preferably shouldered at 18 to retain the plate 17 thereon. An outer face 19 of any suitable or ornamental material may be connected to this plate 17 by any suitable means, that shown in the drawing being a plate of gold whose edges are rolled over those of the inner plate 17. The opposite button member 11 is also provided with a tubular post 20 whose inner end is spread to provide a flange or head 21 and the outer end 23 of the post is reduced, and passed through an opening in the plate 22 and its edge rolled thereover as at 24. The outer plate of this head is attached by having its edge 26 rolled over that of the inner plate 22. It is found in practice difficult to provide a separable button of this character having ball and socket retaining elements that will hold against the strain applied to it, and is strong and durable in construction and one that will retain its spring and yieldability.

An essential feature of my invention is the construction of a pair of spring arms 27 which are preferably struck from spring sheet stock into the concave form illustrated in Fig. 4, said arms being connected together by the laterally extending base member 28 which serves as an anchor or securing portion for retaining this base between the plates of the outer head of its cuff member. These opposite arms 27 are drawn up into somewhat of a trough shape or concavo convex in cross section as best illustrated in Fig. 8, their outer surface 29 being circular and when bent up into the form illustrated in Fig. 6 are shaped to fit snugly into the tubular post 20. The free ends of these arms being shaped as at 30 so

that when in position they form an elongated head with a reduced neck portion adapted to readily enter the opening in the opposite member, the shouldered portion 16 of the member 10 engaging the neck portion of these arms. Another and important feature in the construction of these arms is that their side edges are arranged to come in contact with each other at the point 32, thus providing a fulcrum at a point intermediate their opposite ends, which construction supports the arms and greatly stiffens their spring action and also effectually prevents the spring of the arms from becoming set by constant bending. These arms when bent up into the position illustrated in Fig. 6 naturally stand open somewhat so that they must be forced under a slight pressure into the tube 20 and closed slightly, whereby these arms are always exerting a spreading tendency against the walls of the tube.

My improved construction of elongated spring arms mounted in the tubular post of one of the members renders the construction extremely strong and durable, the arms are firmly anchored at one end in the outer head and are securely protected by the tube through which they pass.

Having thus described one illustrative embodiment of my invention it is understood that the specific terms employed are used in a descriptive sense only and are not for the purpose of limitation, the scope of the invention being defined by the appended claims.

I claim:

1. A separable button comprising two separable members, one provided with a pair of complementary elongated spring arms connected at one end and normally spaced apart at their free ends, said ends being shaped to form a contractible head and means in said arms for supporting each other against a closing action, the other of said button members being provided with a head receiving opening.

2. A separable button comprising two separable members, one provided with two

spaced apart heads connected by a tubular post, a pair of complementary elongated spring arms mounted in said post and extending beyond one of said heads, the free ends of said arms standing normally apart and shaped to form an engaging contractible head, said arms being fulcrumed against each other at a point intermediate their opposite ends, the other of said button members being provided with an opening for receiving and releasably retaining the head ends of said arms.

3. A separable cuff button comprising a pair of button members, each having an inner and outer head spaced and connected by a tubular post, the opening through the inner head into its post having a contracted neck portion, and a pair of elongated resilient arms fitted into and extending through the tubular post of the opposite member from the outer to and beyond its inner head, said projecting ends being normally spaced apart and shaped to form a contractible head to enter the said opening in the opposite member to releasably secure said members together.

4. A separable cuff button comprising two separable members, each having an inner and an outer head spaced apart and connected by a post, one of said members being provided with an opening through its inner head, the stock around said opening forming a contracted neck portion, the post in the other of said members being tubular and its outer head having an inner and an outer wall, a pair of resilient elongated arms connected together and provided with a flange at one end secured between said inner and outer walls of said head, said arms fitting closely in and extending through the tubular post and beyond its inner head, the projecting ends of said arms being shaped to form a contractible head adapted to enter the opening in the opposite member to releasably secure said members together.

In testimony whereof I affix my signature.

CHARLES J. CALLAHAN.
